UNITED STATES PATENT OFFICE.

TIMOTHY McHUGH, OF BOSTON, MASSACHUSETTS, ASSIGNOR OF ONE HALF
TO WARD & CURLEY, OF SAME PLACE.

FLUSHING-VALVE.

SPECIFICATION forming part of Letters Patent No. 363,660, dated May 24, 1887.

Application filed March 25, 1886. Serial No. 196,496. (No model.)

To all whom it may concern:

Be it known that I, TIMOTHY McHUGH, of Boston, in the county of Suffolk and State of Massachusetts, have invented certain new and 5 useful Improvements in Flushing-Valves, of which the following is a specification.

This invention relates to flushing-valves for water-closet tanks, in which a stand-pipe is secured to the valve and projects above the 10 same into the tank, and permits the water rising in the tank above the upper end of the stand-pipe to overflow through said pipe and through the valve and valve-seat.

It is the object of the invention to so improve 15 the construction of devices of the character mentioned that when the valve is closed the valve proper will be certain to bear evenly upon its seat, and when the stand-pipe to which the valve is secured is released after 20 having been raised it will fall with certainty and entire freedom, guiding the valve to its seat, and also to prevent the valve from being moved laterally from its true seat when in its closed position by the action of the water in 25 the tank on the stand-pipe, thus obviating these objections experienced in flushing-valves as heretofore constructed.

To the foregoing ends my invention consists in the improvements hereinafter fully described, and subsequently set forth in the 30 claims.

Of the drawings hereto annexed and forming a part of this specification, Figure 1 represents 35 a side elevation of a flushing-valve embodying my invention. Fig. 2 represents a vertical section of the same, and Fig. 3 is a detail representing a slightly-modified form of the ring encircling the stand-pipe.

The same letters of reference indicate the 40 same parts in all the figures.

In the drawings, *a* represents a raised valve-seat, having its base *b* formed to be inserted, in the usual manner, in the bottom of a water-tank and provided with a central water-way, 45 through which the water flows from the tank when the valve *c* is raised, a suitable outlet-pipe being attached to the lower portion of the base *b* of the valve-seat in any known manner. The valve *c* is annular, and is provided 50 with the usual washer or packing-ring, *d*, adapted to bear on the raised valve-seat *a*, as

shown. The base *e* of the valve, or that portion immediately opposite the valve-seat *a*, and against which the packing-ring *d* rests, is formed as a rim or collar, having a flat surface coinciding with the upper surface or edge of the valve seat. As clearly shown in Fig. 2, the base *e* of the valve is extended laterally beyond the valve-seat *a*, as also beyond the packing-ring *d*, for a purpose to be presently 55 explained. The valve has the stand-pipe *f* attached to it, said pipe projecting upwardly into the tank and passing through the valve, so that the water which rises in the tank above the pipe *f* will escape through the valve-seat 60 and outlet-pipe. The pipe *f* is provided at its upper end with a perforated stud, *g*, to which the chain (not shown) is attached, whereby the stand-pipe and valve are raised.

To guide the valve and stand-pipe in their 65 vertical movements, and to prevent the valve from being removed from its true seat by the action of the water in the tank when closed, I provide a frame consisting of two rings, *h* *i*, connected at their outer edges by bars *j*. The 70 ring *h* of the frame is secured to the base of the valve-seat a short distance below the valve-seat proper, and the upper ring, *i*, which is made broader or wider than ring *h*, extends 75 inwardly and loosely around the stand-pipe. 80

The form of that portion of ring *i* adjacent to the stand-pipe is shown in Fig. 1 as a narrow collar, *k*, and in Fig. 3, showing a modified form of said ring *i*, the part adjacent to the stand-pipe is formed very narrow and with 85 a rounded surface, the object of which construction is to give said ring as little bearing as possible on the stand-pipe, so that the movements of the latter will be attended with the least possible friction, and to avoid the possibility of sediment or any foreign substance accumulating between the guide-ring and stand-pipe, and thus obstructing the free vertical movements of the latter, as would otherwise frequently happen.

The valve proper is constructed so as to move 90 vertically with freedom within the line or circle formed by the bars *j* of the frame, the periphery of the base *e* being extended for this purpose out to or nearly to said bars. By this 100 construction, should the pipe be canted or moved out of a vertical position when it is

raised, it will not bind in ring-guide *i* and be held thereby in an elevated position, and when the valve is closed it cannot be moved laterally from its true seat by the action of the water in the tank upon the upper end of the stand-pipe, as not infrequently happens in the operation of valves of this kind. Furthermore, the valve, when lowered, will at all times be guided by the action of the periphery of the base *e* against the bars *j* to its exact seat, so that the packing-ring *d* will have an even bearing throughout on the raised valve-seat *a*, which would not be the case if the valve were not seated with exactness. By making the valve-seat raised in form I am also enabled to exactly seat the valve with the utmost facility, and by a simple flat packing-ring or washer make a very close or tight valve at a minimum expenditure of labor and money, as has been shown.

20 By my improvement the guide-ring *k* can be made very narrow, and so as to bear with the least possible surface against the pipe, which, with the bars *j* of the frame, for guiding the valve proper, and the very narrow bearing of the base *e* of the valve against said bars, obviates all liability of the stand-pipe and valve becoming "hung" when raised, and makes it certain that the valve will at all times, when lowered, be exactly seated, and by making the 25 valve-seat raised in form a very close or tight valve is obtained by the use of a flat packing-ring of common construction and at little cost. Furthermore, liability of the free vertical movement of the stand-pipe in the guide-ring becoming obstructed by the accumulation there-between of sediment or any foreign matter in the water is overcome, as is also the liability of the valve being moved laterally from its seat by the wave action of the water in the 30 tank on the upper end of the stand-pipe, the guide-bars *f* serving to keep the valve exactly upon its seat.

I am aware that valves of various forms have been constructed for uses similar to that 45 for which my improved valve is adapted, and therefore do not broadly claim a valve of the general construction hereinbefore described,

but confine myself to the combinations set forth in the claims hereunto appended, which embrace the improvement whereby I am enabled to accomplish the objects had in view in constructing the invention.

What I claim is—

1. The combination, with the raised valve-seat, of the stand-pipe exteriorly unobstructed between its upper and lower ends, of the valve secured to the lower end of the stand-pipe, said valve having an extended base, *e*, provided with a narrow periphery, and with a flat surface opposite to and coinciding with the upper surface of the valve-seat, the flat packing-ring *d*, adapted to entirely cover the valve-seat, but not extending to the periphery of the base of the valve, and the frame consisting of the two rings *h* *i* and the connecting bars *j*, the ring *h* being secured to the base of the valve-seat, and ring *i* surrounding the stand-pipe above the valve and having a very narrow surface-bearing with which the pipe is adapted to come in contact, whereby the valve 55 may be easily raised from and fall and be guided with ease and certainty to its exact seat, and all liability of the pipe and valve becoming bound and locked in their guide-bearings when the valve is raised is avoided, 60 as set forth.

2. The combination, with the valve seat *a*, of the valve provided with the extended base *e*, having a narrow periphery, the washer-ring *d*, the stand-pipe *f*, exteriorly unobstructed between its upper and lower ends and secured at the latter end to the valve, valve-seat base *b*, ring *h*, secured to valve-seat base *b*, guide-bars *j*, adapted to contact with and guide the base *e* in its movements, and 65 narrow ring *k*, adapted to contact with and guide the pipe *f* in its movements, as set forth.

In testimony whereof I have signed my name to this specification, in the presence of two subscribing witnesses, this 10th day of March, 1886. 70

TIMOTHY McHUGH.
